UNITED STATES PATENT OFFICE.

FRANKLIN E. CRAWFORD, OF WINCHESTER, MASSACHUSETTS, ASSIGNOR TO BANKERS ELECTRIC PROTECTIVE ASSOCIATION, OF BOSTON, MASSACHUSETTS, A CORPORATION OF MASSACHUSETTS.

ALARM PROTECTION.

Application filed August 12, 1921, Serial No. 491,803. Renewed June 19, 1925.

My invention relates to protective devices for safety vaults and the like, of the class characterized by the employment of an electric-protection layer, normally in circuit with sound or other alarm devices, which on being punctured or otherwise deranged produces an abnormal condition in the alarm circuit, and automatically gives notice that it has been disturbed by some intrusive agency.

Such electro-alarm layers, surrounding or lining the vault space are practically a safeguard against unannounced mechanical penetration, in almost any conceivable emergency; but it is possible for a highly skilled expert, provided he knows or can accurately estimate the thickness of the steel or other exterior sheathing which lies next to the electro-protective layer, to drill carefully and by micrometric measurement exactly through the thickness of such sheathing without penetrating or otherwise disturbing the normal condition of the electro-protective or electro-alarm layer, and thus to expose the said layer by cutting out a panel of the sheathing. It is further possible, though extremely difficult, so to tamper with the electric connections of the electro-alarm layer as to permit its displacement without causing it to give an alarm.

Though the difficulties opposed to the successful penetration of a safety vault protected in the manner above briefly described are so many and so great that no failure of well installed protective devices of the character indicated to give notice of an attempt to break into the vault has been known or reported to me; yet, the aim of vault protective measures is to guard against the remotest possibility of failure, and to concede to skilled safe-breakers the possession of consummate skill and resource. The object of this invention is to render it impossible to expose or even to penetrate to the electro-alarm layer of a vault protecting enclosure, without so deranging its structure as to cause an alarm to be given.

Mechanical tools and instruments of precision, in the hands of an adept, can be limited in their range of action, depth of cut and penetration into materials, with great accuracy. But the penetration, conduction, and diffusion of heat is beyond

such control. The basis of my invention is the establishment of conditions exterior to an electro-alarm layer which encloses a safety vault or the like such that heat must be applied to the covering or sheathing in such a way as to derange an element or elements of the electro-alarm layer, before the covering or sheathing can be penetrated by a mechanical tool, such as a drill.

Further, my invention has for its object not only the protection of the contents of the safe or vault, but the essential structure of the safe or vault itself. This structure, especially in modern installations, is often very costly, and damage to it is a serious item, even though the contents of the safe or vault be not reached. Therefore in the preferred form, my invention affords protection to the safe or vault itself, by providing an external sheathing or casing, which surrounds or overlies the main structure, and is relatively inexpensive to install, or to restore if damaged, and which comprises a covering of tool-resisting material in such proximity to an electro-alarm layer or sheathing inside that heat applied to degrade, destroy or penetrate the tool-resisting material will also derange an element or elements of the alarm-layer. The electro-alarm sheathing, as usually constructed, comprises one or more layers of thin, low melting metal, such as tin-foil, separated by an electrically insulating layer, for example paper, coated or saturated with shellac. The electro-alarm layer is therefore heat-sensitive, as well as susceptible to puncture by mechanical means. Heat disintegrates or traverses the insulation and softens one or more of the conducting elements, of the electro-alarm layer, and establishes a short circuit certain to cause an alarm. In carrying out my invention herein described, any electro-alarm layer susceptible to derangement by heat of its normal electrical relationship with the alarm system of which it constitutes a part, may be employed.

In the drawings hereto annexed, which diagrammatically illustrate my one embodiment of my invention, by way of example

Figure 1 represents, in section, the elements of the protective devices; and shows diagrammatically one type of alarm system

which may be used in connection with the improved protective covering and

Fig. 2, in section, the said devices applied to the exterior of the safe or vault structure.

Fig. 3 is a detail of a portion of Fig. 1 showing switch B in released position; and

Fig. 4 is a modification of the construction of Fig. 2, showing the protective layers spaced apart from the vault proper.

In Fig. 1, E represents the electro-alarm layer as a whole, and C and I represent the inductive and insulating laminæ, respectively, of a typical heat sensitive electro-alarm layer, S the interior casing of a vault chamber, and P that portion of the exterior sheathing which lies outside and next to the electro-alarm layer. I employ the term layer or sheathing as indicative of a structure disposed generally parallel to the surface of the safe or vault and without reference to the specific character or dimensions of such structure, since it may consist of imperforate, foraminous, or reticulated sheet material of any desired thickness of it may consist merely of one or more filaments, strips, or sections of suitable material. The exterior sheathing P may be, for example, a laminated steel plate, of which P', P' are sheets of mild steel, and P², P² sheets of hardened, tool-resisting chrome steel, which will successfully resist the attack of any practicable drill or other penetrating tool.

The experienced safe breaker, on discovering that the plate P comprises tool-resisting steel, will be constrained to employ heat to draw the temper of, or degrade the steel, or in the alternative to relinquish his object.

When heat is applied locally to the plate P for this purpose by the use, for example, of the oxy-acetylene flame it will eventually reach the elements C, I, with the result that the normal structure of the electro-alarm elements is deranged and short circuits, thus giving notice that a break is being attempted.

It will be understood, that while the plate P is shown in the drawing as the only structure exterior to the electro-alarm layer, it may be overlaid with other materials. For the purpose of carrying out this invention, the tool-resisting sheathing is and need be exterior only to the electro-alarm layer.

Preferably, though not necessarily, it will be placed next to the electro-alarm layer, the essential being that the tool-resisting portions of the protective sheet shall be so related to the deformable or destructible, i. e., heat sensitive, element or elements of the electro-alarm layer, that a thermal agency, for example the oxy-acetylene flame applied for degrading or penetrating the tool resisting sheathing will likewise heat the heat sensitive element to a temperature sufficiently

high to cause derangement thereof and consequently sounding of the alarm.

In the preferred form of my invention, the tool-resisting sheathing P, with electro-alarm sheathing associated with it, as above described, will be placed wholly exterior to the essentials of the safe or vault structure, so that an alarm will be given when the tool resisting member of these protective devices is subjected to heat, and therefore before the essential and usually costly safe or vault structure can have been damaged. A vault door for instance, is not infrequently the point of attack; my composite protective sheathing, is secured to the exterior of a vault door, will if attacked by a safe breaker, give the alarm before any portion of the door is damaged except the relatively inexpensive sheathing, and the complicated and costly mechanism within the vault-door structure will remain unharmed. In Fig. 2, S represents generally part of the vault-structure, be it the door or a wall, and P, the composite protective layer shown more in detail in Fig. 1. A modification of the same is shown in Fig. 4, wherein the composite protective layer P is constructed outside of and spaced apart from the vault structure S.

In order to prevent the exterior sheathing from being bodily removed from the electro-alarm layer without giving an alarm, additional alarm means may be provided for this purpose. This means is preferably associated with the electro-alarm layer so as to utilize the same alarm. Thus in Fig. 1 I have shown circuit-closing means arranged to close the circuit between the electro-alarm layers C when the sheathing P is removed, this means comprising an insulating base A mounted in a recess in plate S, a circuit closer B mounted on the base A and an actuator D depending from the circuit-closer into contact with inner plate P'. The ends of circuit-closer B are bent outwardly through openings in the base A and layers I and C, one end normally contacting with the inner layer C and the other end contacting with the other layer C in response to the elasticity of that circuit-closer when the actuator D is disengaged by the inner plate P' upon the removal of the latter.

While the electroprotective layer E has herein been shown as comprising a pair of normally insulated electrical conductors C intended to form elements of a normally open electrical circuit, it is manifestly clear that if a closed circuit alarm system were employed, a single one only of such conducting elements would be necessary, the destruction of such element under the action of heat serving to give the alarm. Likewise in an open circuit system, one of the conducting elements C might well be dispensed with, since the wall of the safe

or vault, if of metal, or the protective layer P could act as one of the conductors of the circuit, and upon breaking down of the insulating material interposed between such metal part and the conductor C a short-circuit would be formed which would give the alarm in the same manner as though the two conductors C were provided.

In Fig. 1, I have illustrated diagrammatically one form of alarm circuit which may be employed in connection with this protective covering. This alarm circuit comprises wires X, Y connected respectively to the conductor elements C. These wires X, Y may be connected to any suitable alarm, for example a bell Z,—a battery W or other suitable source of electrical energy being interposed in one of these wires. This alarm circuit is of the open circuit type and is closed to give the signal by short circuiting of the conductors C with each other. This particular alarm circuit is merely illustrative of any type of alarm circuit which may be found suitable for the purpose whether such circuit be of the open or closed type.

What I claim, and desire to secure by Letters Patent is:

1. In combination with a vault or safe, an outer protective covering therefor comprising a pair of members constituting elements of an alarm circuit, means easily disintegrated by heat normally insulating said members, and a layer of material substantially impenetrable to mechanical agencies arranged in heat conducting relation to one at least of said members and serving to protect said members and the insulating means from mechanical injury.

2. In combination with a vault or safe, an outer protective covering therefor comprising a pair of relatively insulated sheets of metal constituting elements of an electrical alarm circuit, said metallic sheets and the insulating material being of a character such that the plates are readily short circuited upon the application of heat, and a plate of tool resistant material overlying said sheets of metal with their insulation and in heat conducting relation thereto, said plate serving to prevent tampering with said metallic sheets.

3. In combination with a vault or safe, an outer protective covering therefor comprising sheets of metal of low melting point separated by a thin layer of insulation easily destroyed by heat, said layers constituting elements of an electrical alarm system, and a layer of material exterior to said sheets of metal for protecting the latter from mechanical injury.

4. In combination with a vault or safe, a protective covering applicable thereto, said covering comprising an insulated layer of material forming an element of electrical

alarm circuit, a member secured to the vault or safe and normally out of contact with said insulated material, and means permitting said member to contact with said layer of material upon bodily separation of the covering from the vault or safe thereby to energize the alarm circuit.

5. In combination with a vault or safe, a protective covering therefor comprising relatively insulated layers of material forming elements of an alarm circuit, a resilient arm secured to the vault or safe and normally in circuit with one of said layers of material, and means carried by said covering normally operative to prevent contact of said arm with the other layer of material but permitting such contact upon bodily separation of the covering from the vault or safe.

6. An outer protective covering applicable to a vault or safe, said covering comprising at least one electrical conductor forming an element of an alarm circuit, means normally insulating said electrical conductor, and protective material substantially impenetrable to mechanical agencies disposed outwardly of said covering with respect to the conductor to protect the latter from mechanical injury, the conductor being of a character such that it is deranged by the application of heat and being so disposed relatively to said protective material that a thermal agency of sufficient intensity to destroy the protective properties of the latter, when applied to such protective material, will also derange the conductor.

7. In combination with a vault or safe, a layer of material substantially impervious to mechanical agencies disposed adjacent and in protective relation to the outer surface of the vault or safe, and an alarm circuit comprising an electrical conductor disposed at the inner side of said layer of mechanically impervious material, said conductor being of a material such that it may be destroyed by the application of heat, the conductor being electrically insulated and so related to the aforesaid layer of mechanically impervious material that when the latter is subjected to a thermal agency of sufficient intensity to degrade or penetrate it, the conductor will likewise be destroyed.

8. An outer protective covering for a vault or safe comprising at least one electrical insulated conductor constituting an element of an alarm circuit, means normally insulating said conductor, said insulating means being of such character as to lose its insulating qualities when subjected to heat, and protective material substantially impenetrable to mechanical agencies so disposed as to protect the insulating means and the electrical conductor from mechanical injury, said insulated conductor when the protective covering is in operative position, be-

ing disposed adjacent to another conducting part also forming an element of the alarm circuit, said protective material being so disposed relatively to said insulating material that when a thermal agency of sufficient intensity is applied to the protective material to degrade or penetrate the latter, the heat from said agency will break down the insulating material thereby permitting contact of said normally insulated conductor with said other conducting part.

9. The combination with a vault or safe of an alarm circuit, a protective covering for the vault or safe, said covering comprising at least one fusible electrical conductor constituting an element of the alarm circuit, means for insulating said conductor, said insulating means being of a character such that it breaks down when subjected to heat and being so disposed with relation to the protective material that when the latter is subjected to the action of a thermal agency of sufficient intensity to destroy its protective qualities the heat of said thermal agency will also break down the insulating means and fuse the conductor.

10. An outer protective covering for a vault or safe comprising at least one insulating conductor normally constituting one element of an alarm circuit, and protective material substantially impenetrable to mechanical agencies so disposed relatively to the conductor as to protect the latter from injury, said protective material being

so related to the conductor that when subjected to a thermal agency of sufficient intensity to destroy its protective qualities the conductor will likewise be deranged by the heat of said thermal agency.

11. An outer protective covering for a vault or safe comprising a pair of easily fusible conducting elements of an alarm circuit, insulating material easily disintegrated by heat normally insulating said conductors from one another, and a layer of material substantially impenetrable to mechanical agencies in heat conducting relation to said insulating material and conducting elements and serving to protect said insulating material and conducting elements from mechanical injury.

12. In combination with a vault or safe an outer protective covering therefor comprising a layer of insulating material easily disintegrated by heat, an alarm circuit including at least one relatively easily fusible conducting element within and insulated by said insulating layer, and a layer of material substantially impenetrable to mechanical agencies in heat conducting relation to said insulating layer and conducting element and serving to protect said insulating layer and conducting element from mechanical injury, said protective covering being co-extensive with the area to be protected.

Signed by me at Boston, Massachusetts, this 3rd day of August, 1921.

FRANKLIN E. CRAWFORD.
